DECORATIVE PANEL

Herbert P. Lee, Brodbecks, Pa., assignor to Wilton/Lee,
Ltd., Columbia, Pa.

Filed Aug. 17, 1971, Ser. No. 172,613

Term of patent 14 years

Int. Cl. D6—06

U.S. Cl. D6—192

FIG. 1

FIG. 2

FIG. 1 is a plan view of a decorative panel embodying my design, as viewed in front elevation.

FIG. 2 is an edge view of the decorative panel shown in FIG. 1, as seen from the bottom edge thereof, said view being on a larger scale than employed in FIG. 1.

I claim:

The ornamental design for a decorative panel, as shown and described.
